UNITED STATES PATENT OFFICE.

JOSEPH T. UEBBING, OF CLEVELAND, OHIO, AND HOLMES MARSHALL, OF NEW-YORK, N. Y.,
ASSIGNORS TO ADDOGRAPH MANUFACTURING COMPANY, A CORPORATION OF NEW
YORK.

COMPUTING-MACHINE.

No. 888,555.

Specification of Letters Patent.

Patented May 26, 1908.

Application filed February 5, 1907. Serial No. 355,867.

To all whom it may concern:

Be it known that we, JOSEPH T. UEBBING and HOLMES MARSHALL, citizens of the United States, residing at Cleveland, Ohio, and New York city, New York, respectively, 5 have invented certain new and useful Improvements in Computing-Machines, of which the following is a clear, full, and exact description:

10 The object of this invention is to provide an improved means for setting to zero the wheels of adding or computing machines such as shown in the U. S. Patent No. 800,810 granted to Marshall & Uebbing, and a further 15 object is to accompany such setting to zero with a printing mechanism for recording the position occupied by the various wheels before such setting to zero.

Our invention will be pointed out in the 20 claims.

In the drawings, Figure 1 is a partial side elevation of one unit of a computing machine of our prior patent herein referred to; provided with the devices of this invention; 25 Fig. 2 is a section on line 2—2 Fig. 1 showing two such units and a controlling disk of a third; Fig. 3 is a plan view on line 3—3 Fig. 1 taken between the uprights hereinafter referred to, and Fig. 4 is a detail of the resetting wheels.

As shown in the drawings each structural unit of the machine may be composed of a frame 1 in which an indicator shaft 2 and an operating shaft 3 is located. On the indicator shaft there are located gear wheels 4 one of which only is shown in the drawings, but it will be understood that a number of these are usually supplied in machines of this character; and on the shaft 3 there are located a 35 number of wheels having different numbers of teeth, as plainly disclosed in the patent above referred to. For the sake of convenience, in the present improvement we show only one, namely, the wheels having nine 40 teeth. These wheels constitute connecting mechanisms normally incapable of causing the operation of the indicator from the operating shaft. A key 7, one of a series, is provided to control a detent 8 pivoted at 9 in 45 brackets 10 in the top plate 11 of the machine and constitutes a selective mechanism for permitting the engagement of the gear 4 of the indicator with the wheel 6 of the operating shaft 3 all as shown in the patent here- 50 in before referred to.

Upon the indicator shaft 2 there is carried between uprights 12 and 13 three disks, 14 constituting a controlling means for permitting a carrying to the next higher denomination and provided with one tooth 15 to operate a controlling lever 16 of the next denomination. The relative position of the numeral indications of the indicator shaft 2 to the carrying disk 14 is shown by the radial lines in Fig. 2 leading to the figures 9, 0 and 1 inclosed within circles. A cam disk 14 carried by an adjacent frame, similar to frame 1 is shown diagrammatically at the left of Fig. 2. Disk 17 which is a gear wheel preferably of ten teeth, is slidable on the shaft but normally held from sidewise motion by a detent spring 18 operated by such a controlling lever 16, as that before described, and operated from a single toothed disk 14 of the next lower denomination, and a disk 20 having a cut-away portion 21 as shown in Fig. 4 and known as the indicator resetting disk. The toothed indicator resetting disk 20 is slidable on its shaft and is normally held from sliding by a detent spring 22 provided with an 60 arm 23. Springs 24 and 25 on two levers 26 and 27 serve to tend to shift such disks 17 and 20 always sidewise upon their shaft. On the operating shaft 3 there are mounted two disks 28 and 29 fixed in position, one a disk 65 28 having one tooth 30 and is known as a carrying forward disk, and the other 29 a gear wheel having a cut-away portion 31^x and known as a resetting disk. The operation of this resetting device is clearly described in 70 the patent referred to, and only its relation to the present improvement is set forth in this application. The resetting disks 29 on all denominations may be the same in position, but the carrying forward disks 28 on 75 successive denominations should have their single tooth 30 in advanced position as shown in Fig. 2. In that figure assuming the denomination at the left to be tens and the wheel 6 shown to be the ninth connecting 80 wheel, then the single tooth 30 should be positioned as shown so that it would operate shortly after the last movement of the indicator shaft 2 caused by the ninth tooth of the connecting wheel 6, to rotate it an additional tooth by engagement by the disk 28 of the gear 17; which gear 17 will have been 85 previously released from its detent 18 by a raising of the lever 16 from the next lower 90 denomination disk 14 when the indicator 95 110

shaft of the lower denomination has presented¹⁹ upon its indicator. All the denominations may successively release their said gears 17.

- 5 The hundreds carrying forward wheel 28 will have its tooth 30 in position slightly behind the tens as shown in Fig. 2, so that it will come into operation after the carrying forward operation of the tens mechanisms, 10 etc. so that if 9 were the indicated number on tens and hundreds and one was added, then hundreds carrying mechanism would not operate until the tens had carried and shifted the hundreds to zero releasing the carrying 15 gear wheel 17, so that upon the successive operation of the single tooth 30 of the hundreds carrying disk 28 the hundreds unit will successfully carry one to the thousands as will be readily understood.
- 20 Now as we prefer that this type of machine should set forward to zero, it will be obvious that one must prevent a carrying forward during such operation or one would have the digit 1 resulting instead of zero in some cases. 25 Consequently we provide what we term an error preventing mechanism for the resetting mechanism which is adapted to render inoperative the carrying forward mechanism upon the operation of the resetting mechanism. Our preferred form of this error preventing mechanism consists of an extension 31 to the lever 26 having a depending lug 32 and an upwardly extending lug 33. The downwardly depending lug 32 is in the path 35 of a stud 33^x on a rocker 34 pivoted to a block 35 on the bed plate 36 and connected by a lever 37 with a shaft 38 running parallel with the operating shaft 3 and actuated by a lever 39 on a rock shaft 40 which is operated from 40 a resetting lever 41 operated when it is desired to reset the apparatus. The upwardly extending lug 33 engages an arm 23 of the detent 22 controlling the position of the resetting gear 20 on the indicator shaft 2, so that 45 upon rotating the related mechanism on its pivot the detent 22 will release the resetting wheel 20 and at the same time move the controlling lever 26 and its spring 24 away from the carrying forward gear 17 leaving it in inert position upon its shaft, where it will not come into the path of the single tooth 30 of the carrying forward disk 28 during its rotation. It will be obvious by reference to applicant's previous patent above cited that by 50 operating shaft 3 makes one complete revolution to an operation.

As stated herein, a further object of the invention is to leave a record of the last position of the indicators prior to resetting. 60 This is accomplished by placing a resilient platen 42 beneath the indicator head 43 and providing a roller 44 on an arm 45 fixed to a rock shaft 46 connected by a lever 47 with the transverse rod 38 of the resetting mechanism, and providing a second reverse set

48 of figures around the head of the indicator so that a piece of paper placed between the resilient platen 42 and reverse figures 48 will receive an impression upon operation of the resetting mechanism and prior to the operation of the operating shaft. 70

In Fig. 1 I have shown a hand lever 50 fast to the shaft 46 and a spring 51 always tending to return the shaft to the position of that figure. The construction makes it 75 possible not only to do the printing before setting to zero automatically, as before described, but it enables one to print a partial result during an operating at will and independently of the re-setting mechanism. 80

We claim as our invention:

1. In a computing machine comprising an indicator, an operating shaft for the same, a connecting mechanism between said indicator and said shaft and normally incapable 85 of operating said indicator, a selective mechanism for said connecting mechanism, a carrying means controlled by said indicator mechanism for carrying a figure to a higher indicator, in combination with a resetting 90 mechanism and an error-preventing mechanism adapted to render the carrying means inoperative upon the operation of the resetting mechanism.

2. In a computing machine comprising an 95 indicator, an operating shaft for the same, a connecting mechanism between said indicator and said shaft and normally incapable of operating said indicator, a selective mechanism for said connecting mechanism, a carrying means controlled by said indicator mechanism for carrying a figure to a higher indicator, in combination with a resetting mechanism and an error-preventing mechanism adapted to render the carrying means 100 inoperative upon the operation of the resetting mechanism, said related mechanism comprising a system of levers, adapted to simultaneously connect the setting means and disconnect the carrying means. 110

3. In a computing machine comprising an indicator, an operating shaft for the same, a connecting mechanism between said indicator and said shaft and normally incapable 115 of operating said indicator, a selective mechanism for said connecting mechanism, a carrying means controlled by said indicator mechanism for carrying a figure to a higher indicator, in combination with a resetting mechanism and an error-preventing mechanism adapted to render the carrying means inoperative upon the operation of the resetting mechanism, said related mechanism comprising a system of levers, adapted to simultaneously connect the setting means 120 and disconnect the carrying means, and springs to return said levers. 125

4. In a computing machine comprising an indicator, an operating shaft for the same, a connecting mechanism between said indi- 130

- cator and said shaft and normally incapable of operating said indicator, a selective mechanism for said connecting mechanism, a carrying means controlled by said indicator mechanism for carrying a figure to a higher indicator, printing characters carried on said indicator and a platen therefor adapted to print upon operation for setting to zero.
5. In a computing machine comprising an indicator, an operating shaft for the same, a connecting mechanism between said indicator and said shaft and normally incapable of operating said indicator, a selective mechanism for said connecting mechanism, a carrying means controlled by said indicator mechanism for carrying a figure to a higher indicator, printing characters carried on said indicator and a platen therefor adapted to print upon operation for setting to zero, 30 in combination with means for independently printing at will without setting to zero.
10. Signed at Cleveland O., this 31st day of January 1907.
